FIG. 5

FIG. 1 is a front elevation of a portion of a grille embodying my new design, a rear elevation thereof being the same in appearance;

FIG. 2 is a horizontal section, taken along line 2-2 of FIG. 1;

FIG. 3 is a fragmentary horizontal section, taken along line 3-3 of FIG. 1;

FIG. 4 is a front elevation of a portion of a grille or screen also embodying my new design but including a series of upright posts which are spaced apart, rather than being connected together, and also showing an upper frame member for the posts, a rear elevation thereof being the same in appearance; and

FIG. 5 is a vertical section taken along line 5-5 of FIG. 4.

I claim:

The ornamental design for a grille, as shown and described.
